UNITED STATES PATENT OFFICE.

FRED J. LERCH, OF LOUISVILLE, KENTUCKY.

PIPE.

Application filed September 8, 1926. Serial No. 134,202.

This invention relates to pipes of the kind used for smoking tobacco.

In the ordinary type of pipe much trouble is experienced by reason of saliva from the smoker's mouth running down the stem and collecting in the lower part of the stem and the bowl. Also the oils and gums from the tobacco distill off and are drawn down to the bottom of the bowl as the 10 smoker draws on the pipe. This causes the tobacco in the lower part of the bowl to become moist and a heel to form which hinders the free draft through pipe and its stem and also injures and destroys the 15 true flavor of the tobacco being smoked.

Further, this causes the formation of "slugs" of bitter and nauseous matter which is apt to be drawn into the smoker's mouth.

Attempts have been made to overcome 20 these objections by special constructions of pipe bowls but these are not only difficult and expensive to manufacture but are inapplicable to some of the most commonly used pipes such as "corn-cobs."

One principal object of the present invention is to provide a novel construction of attachment for a pipe bowl which may be used with any ordinary pipe and its stem and which includes a novel means for preventing 25 saliva from reaching the tobacco in the bowl and for collecting the oils, gums and resins which distill off the tobacco during smoking; thus ensuring a clean sweet smoke having the full flavor of the blend of tobacco used 30 and also ensuring the absence of a heel and slugs and the complete combustibility of all the tobacco in the bowl.

A second important object of the invention 40 is to provide an improved attachment of this character having a novel arrangement of parts which may be readily separated for cleaning.

A third important object of the invention 45 is to provide an improved device of this kind wherein the construction is such that the pipe may be laid down in any position without moisture from the trap used finding its way into either the bowl or the body of the stem.

A fourth important object of the invention 50 is to provide an improved device of this character which may be manufactured at an extremely low cost, being stamped from thin metal or cast or pressed into molds from some suitable material such as hard

rubber, bakelite or the like, or which can be turned or carved from wood or the like.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a longitudinal section through a pipe and disclosing one form of the invention.

Figure 2 is a similar view disclosing a second form of the attachment.

Figure 3 is a longitudinal section through a third form of the attachment.

Figure 4 is a detail view of the bayonet joint.

In the different forms of the invention here disclosed it will be seen that the attachment comprises a lower or bowl carrying part and an upper or stem receiving part. The lower part includes a vertical tubular portion or well 10 having a bulb 11 on its lower closed end, the bulb being provided with a flat bottom which is preferably level with the bottom of the pipe bowl B. Opening into the well about midway of its height is a lateral inlet tube 12 tapered to fit the opening in the side of the bowl B usually receiving the stem. This inlet tube may have a fully open inlet end as shown in Figure 1 or may be provided with a partially closed end having a small opening 13 therein as in Figure 2.

The upper part or stem fitting consists of an L-shaped tube having a vertical leg 14 and a horizontal leg 15. The vertical leg fits closely within the well 10 and is connected thereto when assembled by a bayonet joint 16 so that the two parts may be easily separated when desired. The vertical leg 14 terminates at its lower end in an inverted frusto-conical portion 17 having a small opening 18 therein. In Figure 1 it will be noted that the leg 14 has a lateral opening 19 which registers with the inlet tube 12 upon the two parts being assembled and that the end 17 is disposed centrally of the well so that an annular channel is formed between the wall of the well and the frusto-conical end. This same opening 19 is pro-

vided in the form shown in Figure 3 but the end 17 is more acutely tapered in the side opposite this opening in this form than in the form shown in Figure 1. In the form 5 shown in Figure 2 the opening 19 is eliminated and the leg 14 is acutely tapered opposite the inlet pipe 12 to provide a channel 20 for directing the products of combustion of the tobacco into the lower part of the 10 well.

In each form the horizontal leg 15 receives the stem S and preferably this leg has its interior diameter the same size and shape as the stem hole in the bowl B so 15 that the stem supplied with the pipe may be removed from the bowl and the attachment fitted to the pipe and the same stem fitted to the attachment.

In use it will be seen that the products 20 of combustion, in Figures 1 and 3 pass into the leg 14 and any moisture drops down into the bulb 11 through the opening 18. In Figure 2 the products pass down into the well below the lower end of the stem holding part and the moisture collects there, the smoke passing upwardly through the hole 18. In all forms any saliva will pass down through the hole 18 into the bulb.

From time to time the parts are separated 30 and the bulb emptied and washed out. Thus, no matter in what position the pipe may be laid aside none of the contents of the bulb can flow into the stem nor, in the forms shown in Figures 1 and 3, into the 35 bowl. Thereby the tobacco is always dry and the formation of slugs prevented.

There has thus been provided a simple and efficient device of the kind described and for the purpose specified.

40 It is obvious that minor changes may be made in the form and construction of the invention without departing from the material spirit thereof. It is not, therefore, desired to confine the invention to the exact 45 form herein shown and described, but it is desired to include all such as properly come within the scope claimed.

Having thus described the invention, what is claimed as new, is:

50 1. An attachment for pipes including an upper tubular part and a lower tubular part detachably connected, said lower part comprising a vertical well closed at its bottom, and a laterally extending inlet tube communicating with the well between its ends,

said tube having its free end arranged to fit into the stem opening of a pipe bowl, said upper part having a vertical leg extending into the well and terminating in a frusto-conical portion extending below the inlet tube and provided with a small hole affording communication with the lower part of the well, said hole being of less diameter than the bore of the upper tubular part, said upper part also having a lateral leg at 65 its upper end adapted to receive a pipe stem.

2. An attachment for pipes including an upper tubular part and a lower tubular part detachably connected, said lower part comprising a vertical well closed at its bottom 70 and there enlarged to form a liquid receiving bulb, and a laterally extending inlet tube communicating with the well between its ends, said tube having its free end arranged to fit into the stem opening of a pipe 75 bowl, said upper part having a vertical leg extending into the well and terminating in a frusto-conical portion extending below the inlet tube and provided with a small hole affording communication with the lower 80 part of the well, said hole being of less diameter than the bore of the upper tubular part, said upper part also having a lateral leg at its upper end adapted to receive a pipe stem.

3. An attachment for pipes including an upper tubular part and a lower tubular part detachably connected, said lower part comprising a vertical well closed at its bottom and there enlarged to form a liquid receiving bulb, and a laterally extending inlet tube communicating with the well between its ends, said tube having its free end arranged to fit into the stem opening of a pipe bowl, said upper part having a vertical leg extending into the well and terminating in a frusto-conical portion extending below the inlet tube and provided with a small hole affording communication with the lower 95 part of the well, said hole being of less diameter than the bore of the upper tubular part, said upper part also having a lateral leg at its upper end adapted to receive a pipe stem, said vertical leg fitting closely against the wall of the well at the inlet tube opening and being itself provided with an opening registering with said inlet tube.

In testimony whereof I affix my signature.

FRED J. LERCH.
